UNITED STATES PATENT OFFICE

130,175

DESIGN FOR AN ENCLOSURE FOR SANITARY ROLLED RUBBER GOODS

Carl J. Schmid, New York, N. Y.

Application January 17, 1940, Serial No. 89,523

Term of patent 14 years

To all whom it may concern:

Be it known that I, Carl J. Schmid, a citizen of the United States, residing in New York, in the county of New York and State of New York, have invented a new, original, and ornamental Design for an Enclosure for Sanitary Rolled Rubber Goods, of which the following is a specification, reference being had to the accompanying drawing forming part thereof, in which:

for sanitary rolled rubber goods, showing my new design;

Figure 2 is a top plan view thereof;

I claim:

The ornamental design for an enclosure for sanitary rolled rubber goods, as shown.

CARL J. SCHMID.
